METHOD AND APPARATUS FOR BURNING
FINE SOLIDS

Charles S. Gladden, Brooklyn, N. Y.

Application December 11, 1945, Serial No. 634,281

2 Claims. (Cl. 110—165)

1

This invention relates generally to the art of solid fuel combustion and particularly to a new method of, and new apparatus for, burning the carbon in the fly-ash collected from the gases of a stoker fired furnace.

A serious problem has long existed in the operation of stoker fired furnaces with respect to the collection and burning of finely divided solids commonly known as fly-ash, which is carried out of the combustion chamber of the furnace by the gases. Much of this fly-ash can be collected in hoppers in the rear passes of the boiler setting or at the base of the stack of the furnace. This fly-ash contains considerable quantities of combustible carbon. The fly-ash which collects in the forward passes of the boiler may contain from about 80% to about 90% of combustible carbon, while the fly-ash which is collected in the rear passes of the boiler and that collected adjacent to the stack base may contain combustible carbon from about 60% to about 75%. Generally speaking, the percentage of carbon content in the fly-ash increases with the rate of combustion and increases as the size of the coal decreases. In all cases, however, the quantity of the fly-ash and the carbon content of the fly-ash are so great that marked inefficiency results if the carbon content of the fly-ash is not burned in the combustion chamber.

Many efforts have been made by highly skilled workers in the art heretofore to burn the fly-ash and various proposals have been made to the end of accomplishing that result. However, so far as I know, none of these efforts or proposals has been entirely satisfactory.

The present invention is predicated on a new mode of operation and on the use of a new apparatus. According to the present concept the fly-ash is continuously withdrawn from collecting hoppers and moved toward the combustion chamber and is continuously mixed with sufficient air for substantially complete combustion of the carbon content of the fly-ash and the mixture is delivered into the combustion chamber under the rear arch where combustion is most active and the temperatures are highest, and delivery of this mixture is directed forwardly over the fire in the general direction of travel of the furnace gases. Apparatus is provided for continuously feeding fly-ash toward the combustion chamber for mixing the ash with air for combustion, preferably preheated air, and for discharging this mixture forwardly in the hottest portion of the combustion chamber in the general direction of the travel of the furnace gases.

5 This new method and apparatus has been found to be quite successful in actual commercial use both as regards the utilization of large quantities of the carbon content of the fly-ash and in the maintenance of uniform operating conditions and high efficiency of the furnace and boiler.

In the drawings which accompany and form a part of this specification,

Figure 1 is a fragmentary rear elevational view, partly in section, taken on line 1—1 of Fig. 2 and showing a stoker fired furnace embodying the present invention;

Figure 2 is a longitudinal view, partly in section, taken on line 2—2 of Fig. 1;

Figure 3 is a fragmentary plan view, partly in section, taken on line 3—3 of Fig. 1;

Figure 4 is a side elevational view, partly in section, of one of the traps of Figs. 1 and 2;

Figure 5 is an end elevational view, partly in section, of the trap of Fig. 4 with the associated conduits; and,

Figure 6 is a diagrammatic partly sectional view of conventional apparatus with which the apparatus of Figs. 1 to 5 may be used.

The furnace of Figs. 1 and 2 may be of conventional construction. As shown, it comprises a conventional chain grate stoker 1, the upper grate of which constitutes the base of combustion chamber 2 of the furnace having a rear end wall indicated at 3 and a front end wall indicated at 4. The rear arch of the furnace 5 extends from the rear wall 3 to the furnace throat 8 and thence up along inclined wall 9. The upwardly extending front wall 10 of the furnace diverges from wall 9 and, together therewith, defines the furnace throat 8. Two vertical side walls 12, parallel to each other and extending along each side of the stoker, complete and define the limitations of the combustion chamber 2. The construction of the rear arch 5 and rear wall 9 and front wall 10 may be of solid refractory or of refractory blocks suspended from structural supporting steel, or they may be provided with the conventional water tubes along the inner surfaces which are connected with headers and through which boiler water circulates to reduce the temperature and protect the refractory from excessively high temperature.

Hopper 15 at the front of the furnace is provided to receive coal from a storage hopper (not shown). The lower end of this hopper is adjacent to the top of moving grate 1 which travels under the fuel hopper from the front toward the rear and thus coal which forms the fuel bed 16

is supplied to the grate as the latter enters combustion chamber 2. It will be understood that air for combustion of the coal on the grate is blown into forced draft compartments 17 beneath the coal laden, rearwardly moving reach of the grate 1, and flows up thru the bed of fuel affording oxygen for combustion of the fuel on the grate.

Fig. 6 shows, partly diagrammatically and partly in section, conventional apparatus with which the apparatus of Figs. 1 to 5 may be used. This Fig. 6 shows part of the combustion chamber 2, which is shown more completely in Fig. 2, the throat 8, a boiler having baffles 18a, 18b and 18c, four drums 19, a front fly-ash hopper 20a below the second baffle 18b, a rear fly-ash hopper 20b located on the rear side of baffle 18c and below a duct leading upward to an air preheater 21. Fig. 6 also shows an induced draft fan 22 which causes furnace gases to flow around baffles 18a, 18b and 18c through air heater 21 and propels those gases through duct 23 to the base of stack 24. The base of the stack is provided with a hopper 24a which is connected by a downwardly extending conduit 24b to hopper 20b into which fly-ash from the stack may be delivered. A forced draft fan 24c discharges air through preheater 21 and thence into housing 39, presently to be described, whence such air is delivered through conduits 38 and thence into conduits 34.

In installations where induced draft fans are present and where there is a greater negative draft in one of the rear passes of the boiler than at the base of the stack, the fly-ash which is collected in a hopper at the base of the stack may be continuously discharged by gravity directly into the fly-ash hoppers of such rear passes of the boiler, and thence delivered into the revolving traps.

From the lower portion of each hopper 25 comprising hoppers 20a and 20b a conduit 26 extends downwardly and opens into a trap 27 (see Figs. 4 and 5). Each trap 27 has a shaft 28 extending axially therethru and mounted in bearings 29 on the outer sides of the trap. Shaft 28 carries blades 30 spaced therearound at intervals, for example, 90 degrees apart. The shaft and blades constitute a rotatable feeder in trap 27 for continuously receiving fly-ash from hopper 25 and delivering it in successive quantities to conduit 31 leading downwardly from the bottom portion of the trap. The diametrical dimensions of wings 30 are such that there is a small clearance between the outer edges of the wings and the inner surface of trap 27. This clearance permits free rotation of the shaft and blades and prevents any substantial flow of gases from the low negative pressure region in the combustion chamber up to the much lower pressure region in the fly-ash collecting hoppers. The lower end of conduit 31 is connected to a conduit 32 extending at an angle to conduit 31 and conduit 32 is connected thru swivel joint 33 to conduit 34 which extends thru arch 5 into the top portion of combustion chamber 2. A header 36 communicates with the upper end of conduit 32 thru conduit 37 and serves to admit air into conduit 32, where it mixes with fly-ash discharged from conduit 31. Air may be supplied to header 36 thru conduit 38 from a housing 39, which may be a part of a forced draft system of the furnace or from an air preheater or forced draft fan. Preferably, the air delivered into conduit 32 is preheated so that when the mixture of air and fly-ash

is discharged into the combustion chamber the air will not tend to exert any material cooling effect on the gases in the combustion chamber.

It will be noted that conduits 32 and 34 are inclined downwardly toward the throat end of the combustion chamber and that by reason of this inclination the mixture of air and fly-ash is projected into the combustion chamber in the general direction of travel of the gases toward the front of the furnace, as illustrated in Fig. 2. The general travel of the furnace gases is indicated by broken arrows and the entering fly-ash is indicated by solid arrows intermingling with the broken arrows and flowing in the same general direction toward the throat 8 of the combustion chamber. It will be noted that certain solid arrows, indicating the heavier particles of carbon and fly-ash drop to the stoker grate in a zone where combustion is most actively taking place. As indicated, conduits 34 extend thru the roof or arch 5 of the furnace over the region of the fuel bed where the combustion is most rapid and the temperatures of the gases are highest. Preferably, sufficient air is admitted into conduits 32 to supply the oxygen required for substantially complete combustion of the carbon in the fly-ash with which it mixes. In this manner the finer particles of fly-ash cinders are surrounded with air when they enter the combustion chamber and burn almost immediately, while the larger particles of fly-ash cinders, which do not burn in suspension may fall onto the burning fuel bed where their burning will be completed.

As is shown in Fig. 1, the rotating elements of two adjacent traps 27 may be connected together for simultaneous operation by a single geared motor. Such a motor is shown at 40 and is directly connected to shaft 41 which in turn is connected to shaft 28 of the adjacent trap 27. The shaft of that trap may be coupled by shaft 42 to the shaft of an adjacent trap.

As is better shown in Fig. 3, shaft 41 may be connected as by sprocket wheels and chain belt 45 to adjacent trap 27, and the shaft from this latter trap may be connected by shaft 46 to another trap 27. In that manner one motor may drive the revolving elements of four traps. It will be obvious that additional traps may be actuated in a similar manner if desired.

The operation of the above described apparatus is substantially as follows: With stoker 1 in operation and fuel burning thereon, gases flow up thru throat 8 around the boiler tubes in the first pass thence over the first baffle and around the boiler tubes in the second pass. Under the lower edge of baffle 18b where the furnace gases change direction from a downward movement through the second pass to an upward movement through the third pass the cinders and fly-ash which are carried out of the combustion chamber 2 by the furnace gases are precipitated or deposited into the front fly-ash hopper 20a. Some of the finer and lighter fly-ash continuing with the furnace gases pass over the rear baffle 18c into the rear gas passage and are mostly thrown down into the rear fly-ash hopper 20b when the gases again change direction from a downward to an upward movement before passing on to the suction of the induced draft fan 22. The induced draft fan discharges the gases into the base of the stack thence to the atmosphere from the top of the stack. The fly-ash delivered into hoppers 25 is continuously fed thru traps 27 by rotation of shafts 28 and blades 30 into conduits 31 where the fly-ash is mixed

with air which preferably has been preheated and the mixture passes thru conduits 34 into the hottest part of the combustion chamber. The inclination of conduits 34 directs the mixtures into the combustion chamber in the direction of travel of the gases above the stoker. The carbon in the lighter particles burns while they are mixing with the gases. The larger particles which are too heavy to remain suspended in the gases fall onto the burning fuel on the stoker grate and the carbon in these larger particles burns partly while the particles are in the gases and partly while the particles are on the ignited fuel. The courses of travel of the large and small particles are indicated by the arrows in Fig. 2.

One important function of the revolving trap is to prevent back draft from interfering with the continuous gravity flow of fly-ash from hoppers 25 into the combustion chamber. Since there is a higher gas pressure in the combustion chamber than in hoppers 25, or in the fly-ash hoppers which communicate with those hoppers, there would be a tendency for gases to flow from the combustion chamber up thru conduits 34 and hoppers 25. This tendency, however, is overcome by the small clearance between the traps and their revolving portions and thus furnace gases are prevented from imposing any noticeable resistance to the free gravity flow of fly-ash from traps 27 into the combustion chamber.

Having thus described my invention so that others skilled in the art may be able to understand and practice the same, I state that what I desire to secure by Letters Patent is defined in what is claimed.

What is claimed is:

1. The method of recovering and burning fly-ash which comprises the steps of removing fly-ash from furnace gases while on their way from the throat of a combustion chamber to a stack and depositing such ash in a hopper, feeding ash continuously from the hopper in a restricted stream by gravity while mechanically preventing opposed flow of furnace gases toward said hopper, continuously mixing with said flowing stream of ash an amount of air approximately sufficient for substantially complete combustion of the carbon contained in the ash in said stream, and continuously discharging the resulting mixture of ash and air into the furnace combustion chamber at a place remote from said throat and on

a line directed downwardly at a substantially acute angle to the horizontal and toward said throat.

2. Apparatus for recovering and burning fly-ash comprising a furnace having a combustion chamber defined in part by a front wall, a rear wall, side walls, and a roof sloping upwardly from the rear wall toward the front wall, a substantially horizontal stoker extending from the front wall toward the rear wall and beneath said roof, a stack, a fly-ash collecting hopper between the chamber and stack, a conduit extending downwardly from said hopper at such an angle that fly-ash will flow freely along it, said conduit projecting through the sloping roof over the stoker at a substantial acute angle to the top of said stoker and in a direction opposed to the direction of travel of the stoker, a rotatable trap in said conduit for feeding fly-ash from the hopper into said conduit while preventing counterflow of furnace gases from the conduit into the hopper, and inlet means for admitting air under pressure into the conduit to mix with and propel fly-ash therealong and into said chamber.
